UNITED STATES PATENT OFFICE.

LUDWIG BAJDE, OF LEIPZIG-GOHLIS, AND GUSTAV KARL HENNIG, OF BÖHLITZ-EHRENBURG, NEAR LEIPZIG, GERMANY, ASSIGNORS TO THE FIRM OF LUDWIG HUPFELD AKTIENGESELLSCHAFT, BÖHLITZ-EHRENBURG, NEAR LEIPZIG, GERMANY.

BOW FOR PIANO-VIOLINS.

1,228,737.

Specification of Letters Patent.

Patented June 5, 1917.

Application filed July 3, 1914. Serial No. 848,813.

To all whom it may concern:

Be it known that we, LUDWIG BAJDE, a subject of the Emperor of Austria, and residing at 23 St. Privatstrasse, Leipzig-Gohlis, and GUSTAV KARL HENNIG, a subject of the King of Saxony, residing at Bielastrasse 1, Böhlitz-Ehrenberg, near Leipzig, Germany, have invented certain new and useful Improvements in and Relating to Bows for 10 Piano-Violins; and we do hereby declare the following to be a full, clear, and exact description of the invention.

This invention relates to the endless bowing bands of mechanically bowed musical 15 instruments, such bands being formed of hanks of horse hair or similar material. The invention also relates to the guiding of said bowing bands.

Figure 1 of the accompanying drawings 20 is a perspective view illustrating a method of uniting the ends of horse hairs into an endless bowing band according to the invention.

Fig. 2 is a sectional side view, 25 Fig. 3 a part transverse section, and

Fig. 4 a plan illustrating a constructional example of the improved bowing apparatus associated with a stringed instrument.

Fig. 5 is a similar view to Fig. 3, and 30 Fig. 6 a part side elevation illustrating a constructional example of an arrangement for pressing the bowing band down toward the strings of the instrument to be bowed.

Figs. 7 and 8 illustrate two other constructions of the improved bowing band. 35

Fig. 8^a is a section on lines 8—8 of Figs. 7 and 8.

Fig. 9 is a plan view showing the crossing of two adjacent hairs.

Fig. 10 shows the two ends of the hairs knotted and secured to a tab. 40

Fig. 11 shows an additional tab to effect the crossing of the hairs between their ends.

Fig. 12 is an elevation, and

Fig. 13 is a plan view of another device used in constructing the endless hair bow. 45

To produce an endless horse hair bowing band *a*, Fig. 2 four hanks or sets of horse hair 1, 2, and 3, 4 arranged for example as 50 shown in Fig. 1 around eight pins *c* placed one at each corner of two rectangles crossing

each other in the form of a cross. The pins *c* are fixed vertically in a base plate *b* or the like, and the hanks of hair are so connected to each other in pairs by tabs *d* of soft 55 leather or the like, that each pair forms the sides of a rectangle. The connecting tabs *d* are arranged on the sides of the rectangles located beyond the inner rectangle formed by the crossing of the two rectangles, and 60 the hairs of each hank preferably alternate with and cross those of the other hank separately. After removal of the hanks so connected to each other from the pins, the hairs of each hank appear connected with those 65 of a second hank and are so crossed in and out with those of the two other hanks that the connecting tabs *d* are everywhere situated on the outside.

The drawing of each separate hair into 70 the tabs *d* may be effected with advantage by means of a sewing needle after which each separate hair is interlaced into the tab so as to produce a secure connection.

The endless bowing band *a* produced in 75 this way is passed with the smooth inner side over two rollers *f* and *g* mounted in a frame *e*, so that the connecting tabs *d* are located on the outside and do not come into direct contact either with the rollers or with the 80 stringed instrument *h* arranged between them.

The arms *c*¹ of the frame, in which one of the rollers *f* is mounted, are connected to each other by means of a yoke *i* which embraces the corresponding end of the base member *e* of the frame and can be moved longitudinally being guided by screws *k* working in slots *j* of the yoke *i* and fixed in the frame plate, so that the tension of the 85 endless bowing band can be regulated according to requirements by means of the adjusting screws *m*.

The arms *e*¹¹ of the frame, in which the roller *g* is mounted, are carried on centers *n* 95 fixed in the side members of a vertical frame *o*. The base *e* rests by means of a spring *p* located below the arms *c*¹ upon a fixed part *q* of the instrument frame or the like and is connected by means of a link *r* or the like to 100 depressible key *s* constructed in the form of a one-armed lever and by means of which

the bow carrying frame together with the roller f and the bowing band a can be rocked downward against the pressure of the spring p for the purpose of pressing the 5 bowing band against the strings t Figs. 2 and 4 of the instrument.

This depression of the bowing band at the point where it bows the strings may however be effected by means of each key u of a 10 keyboard operating the instrument, see Figs. 5 and 6. In such a construction each key is provided with a downwardly extending pusher u^1 , which, as shown in Fig. 5, presses down a frame y which draws down the 15 frame e together with the roller f and the bowing band a .

The depression of the bowing band may in some cases be effected pneumatically in which case a valve w is opened each time by 20 the depressed frame y , see Fig. 6.

The rollers f and g may be driven continuously by means of an electromotor, by foot or hand operated mechanism, the raising of a weight, clockwork, etc., or the rollers 25 may be moved to and fro by means of two pneumatic devices.

The frame o is carried on vertically mounted centers x , see Fig. 3, about which it can be rocked together with the frame e by 30 means of a pedal z , see Fig. 4, to the right and left, in order to move the bowing band out of its normal position shown in full lines into a position nearer the bridge h^1 of the instrument which position is indicated by dotted lines. This operation can be effected while the instrument is being 35 played. Instead of the pedal z the shifting of the point at which the bowing band is brought into contact with the strings of the 40 instrument may be effected by other suitable arrangement, for example pneumatically by means of a bellows.

Instead of being in the form shown in Fig. 1 the bowing band may be so constructed 45 that in addition to the tabs d at the points where the hanks are connected, a tab of soft leather or the like is inserted between each two points where the hanks cross as shown in Figs. 7 and 8. This construction of the bowing band enables the number 50 of points of connection to be reduced to a minimum and favors the obtaining of a uniform tension of the bowing band.

In the construction shown in Fig. 7 two 55 hanks of horse hair 1 and 2 are crossed with each other as indicated at the points marked 10. In each hank the ends of the hairs are connected by means of a tab d of soft leather or the like. Since however the two 60 hanks cross each other at four points 10 there are opposite the connecting tabs d other tabs d^1 and d^2 respectively of soft leather or the like, which, like the tabs d , prevent the hairs of both hanks from pass-

ing through each other and becoming parallel, whereby they afford the necessary support to the whole of the hairs of the bow when taut.

The bowing band shown in Fig. 8 consists of a single hank of hair, the ends of which 70 are connected to each other by means of a connecting tab d , whereby a uniform tension of the hairs of the bow is secured over the whole length thereof. The entire hank is formed into two circular loops, the parts 75 of which cross each other several times, and between every two crossing points 10 where the hanks cross each other is arranged a tab d^1 , d^2 , d^3 , d^4 respectively by means whereof the crossing hanks of hair are held apart. 80

To affix the tabs d^1 , d^2 , etc., a bowing band of the kind described is stretched over the face of a disk 5, Fig. 12, which is provided at the necessary points with corresponding recesses 6 which are bridged over by the hairs. 85 At these points the hairs are held separated as shown by the pins c^1 and the tabs are pushed through between the hairs being drawn through alternately upward and downward. The arrangement shown in 90 Fig. 1 may however also be used for the production of a bowing band of the kind described, the tabs d^1 , d^2 , etc., not however being used for connecting the ends of the hair. 95

We claim:

1. An endless bow for piano-violins having sets of hairs crossing one another and means inserted between said sets intermediate the crossing points of the hairs to 100 maintain them crossed.

2. An endless bow for piano-violins, comprising hanks of hair, the connecting points of said hanks being outside the effective surface, a tab of soft material forming a connecting member for the ends of the hairs and to which said ends are secured. 105

3. An endless bow for piano-violins, comprising two sets of crossed hairs, the hairs of one set alternating with those of the other set, pieces of soft flexible material to which the ends of the hairs of a set are secured, and additional pieces of soft material interposed between the sets of hairs at intervals 110 between the ends of said hairs and maintaining said sets in crossed relation. 115

4. In an endless bow for piano-violins, crossed sets of hairs, flexible tabs to which the opposite ends of the hairs of each set are respectively connected and similar tabs interposed between the sets between the crossing points of the two sets. 120

5. In an endless bow for piano-violins, sets of crossed hairs forming an endless band, and tabs of flexible material inserted between the sets and to which one portion of a set on the side of the bowing surface is secured at points between the crossing points 125

of the sets, thereby holding the sets in proper relation and providing a continuous bowing surface of hair.

6. An endless bow for piano violins formed of hairs arranged in loops or turns, the hairs of one loop or turn alternating with and crossing those of the other loop or turn, and a tab of soft flexible material arranged be-

tween the crossing points of the hairs of the turns and to which the hairs outside the effective surface of the bow are connected. 10

In testimony whereof we have signed our names to this specification.

LUDWIG BAJDE.

GUSTAV KARL HENNIG.
